(57) **CLAIM**

The ornamental design for the shaving razor, as shown and described.

DESCRIPTION

FIG. 1 is a front perspective view of the shaving razor, showing the new design;

FIG. 2 is a front view of the shaving razor;
FIG. 3 is a rear view of the shaving razor;
FIG. 4 is a side view of the shaving razor;
FIG. 5 is another side view of the shaving razor;
FIG. 6 is a top view of the shaving razor;
FIG. 7 is a bottom view of the shaving razor;
FIG. 8 is a front perspective view of a second embodiment of the shaving razor;
FIG. 9 is a front view of the second embodiment of the shaving razor;
FIG. 10 is a rear view of the second embodiment of the shaving razor;
FIG. 11 is a side view of the second embodiment of the shaving razor;
FIG. 12 is another side view of the second embodiment of the shaving razor;
FIG. 13 is a top view of the second embodiment of the shaving razor;
FIG. 14 is a bottom view of the second embodiment of the shaving razor;
FIG. 15 is a front perspective view of a third embodiment of the shaving razor;
FIG. 16 is a front view of the third embodiment of the shaving razor;
FIG. 17 is a rear view of the third embodiment of the shaving razor;
FIG. 18 is a side view of the third embodiment of the shaving razor;
FIG. 19 is another side view of the third embodiment of the shaving razor;
FIG. 20 is a top view of the third embodiment of the shaving razor; and,
FIG. 21 is a bottom view of the third embodiment of the shaving razor.
The broken lines are shown for illustrative purposes only and form no part of the claimed design.
